(57) **CLAIM**

The ornamental design for a front face of a vehicle wheel, as shown and described.

DESCRIPTION

FIG. 1 is a perspective view of a wheel showing my new design; and,

FIG. 2 is a front view thereof.

In the drawings, broken lines shown in the drawings depict environmental subject matter

In the drawings the broken lines depict portions of the wheel that form no part of the claimed design.

1 Claim, 2 Drawing Sheets**FIG. 1**

FIG. 2
